United States Patent Office.

DANIEL S. BROWN, OF ASTORIA, OREGON.

Letters Patent No. 95,877, dated October 19, 1869.

IMPROVED BOAT-DETACHING APPARATUS.

The Schedule referred to in these Letters Patent and making part of the same

To all whom it may concern:

Be it known that I, DANIEL S. BROWN, of Astoria, in the county of Clatsop, and State of Oregon, have invented a new and improved Boat-Detaching Apparatus; and I do hereby declare that the following is a full, clear, and exact description thereof, which will enable others skilled in the art to make and use the same, reference being had to the accompanying drawings, forming part of this specification, in which—

Figure 1 represents a vertical longitudinal section of my improved boat-detaching apparatus.

Figure 2 is a plan or top view of the same.

Similar letters of reference indicate corresponding parts.

This invention relates to a new device for facilitating the instantaneous detachment of boats from their davits; and consists in such a new combination of retaining-jaws with rods, levers, and catch, that the simultaneous detachment of both ends will be certain, and accidents on account of improper operation impossible.

On each end of the boat A is arranged a stationary jaw, B, which has a projecting ear, a, as shown.

To the ears a of the stationary jaws are pivoted, on the inner side of the boat, the movable jaws C C, which have their lower ends connected, by rods b b', re-

spectively, with the opposite ends of a bar, D, which is at its middle pivoted by a pin, c, to some fixed part of the boat.

The bar D is at one end, by a rod, d, connected with a lever, E, which is pivoted within the boat.

By swinging the lever E on its pivot e, the bar D will also be swung, so as to open or close the jaws both at once.

When the jaws are closed, as in fig. 1, to suspend the boat from the davits, the lever E is locked by a catch, F, which is pivoted to the under side of a seat, or in other equivalent manner.

The jaws should be oval, as shown, or V-shaped, so as to instantly release the ring when opened.

Having thus described my invention,

I claim as new, and desire to secure by Letters Patent—

The combination of the stationary jaws B and pivoted jaws C with the rods b b', bar D, lever E, rod d, and catch F, all arranged and operating substantially as herein shown and described.

DANIEL S. BROWN.
